UNITED STATES PATENT OFFICE.

WILMER W. SALMON, OF CHICAGO, ILLINOIS, ASSIGNOR TO THE HALL SIGNAL COMPANY, A CORPORATION OF MAINE.

SIGNALING SYSTEM FOR SINGLE-TRACK RAILWAYS.

SPECIFICATION forming part of Letters Patent No. 692,915, dated February 11, 1902.

Application filed July 21, 1894. Serial No. 518,218. (No model.)

To all whom it may concern:

Be it known that I, WILMER W. SALMON, a citizen of the United States, and a resident of Chicago, in the county of Cook, State of Illinois, have invented certain new and useful Improvements in Signaling Systems for Single-Track Railways, of which the following is a specification.

My invention relates to electric block-signaling systems for single-track roads; and it has for its object to provide a more reliable system of this nature than has been heretofore known.

It consists of the various features herein-after pointed out.

The system herein described is a modification of an electric signaling system described in an application filed simultaneously herewith, the principal difference being that in the present system the signal operating or controlling circuits stand normally open, with the signals at "danger," while in the other system the signal-circuits are normally closed and the signals at "safety." To further distinguish the cases, I arbitrarily designate this case "Case No. 6" and the other case "Case No. 5."

The accompanying drawing represents diagrammatically the preferred embodiment of my present invention.

In the diagram the track is provided with a series of signals A C E, &c., to signal trains running in the direction of the arrow, or outrunning trains, and a series of signals F D B, &c., to signal the trains running in the opposite direction, or inrunning trains. The signals A C E, &c., may be therefore termed "outrunning" signals, and the blocks which they guard "outrunning" blocks, the signals F D B, &c., being termed "inrunning" signals and their blocks "inrunning" blocks. Of course the terms "inrunning" and "outrunning" could be applied to either series of signals, and the terms are chosen and applied merely for the purposes of description. The signals are provided each with a signal-circuit for operating or controlling the signal, and these signal-circuits are controlled by the passage of a train by means of track-circuits. There are various types of track-circuits which might be employed in carry-

ing out the broad spirit of my invention—for example, track-circuits permanently unbroken, normally closed, or normally broken, track-circuits operated by track instruments, or track-circuits, including the rails of the track. The track-circuits shown in the drawing include the rails of the track and are permanently unbroken, their magnets being shunted by the train. The track is divided into subsections each including a magnet and battery. These subsections are lettered N O, O P, P Q, Q R, R S, S T. The batteries for their track-circuits are numbered 1, 9, 17, 25, 33, and 41, and their magnets are numbered 5, 13, 21, 29, 37, and 45, respectively. The signals are preferably arranged on opposite sides of the track, as shown. The signals on one side of the track act as danger-signals to trains advancing in one direction and as opposing signals to trains advancing in the other. Thus signals A, C, and E act as danger-signals to trains proceeding in the direction of the arrow and as opposing signals to trains proceeding in the other direction, while signals B, D, and F act as danger-signals to trains proceeding in the reverse direction to that of the arrow and opposing signals to trains proceeding in the direction of the arrow. For the sake of conciseness the terms "danger-signal" and "opposing signal" will be used in the specification with the meaning above given.

My improved devices will be best explained by describing in order, in connection with the drawing, the successive operations of a train upon these devices in passing over the sections of track represented. It will be understood that in the form of my devices shown in the drawing the various signals there shown are in their normal position at "danger" and are put at "safety" by the closing of normally open signaling-circuits.

First operation, on the train entering subsection N O at N in the direction of the arrow.— As soon as the wheels strike the rails of the subsection N O the relay 5 in the rail-circuit of battery 1, wire 2, rail 3, wire 4, relay 5, wire 6, rail 7, wire 8, back to battery is in the ordinary way demagnetized. The circuit-maker 49 thereupon drops on the contact-point of the wire 50, thus closing the former break

at that point in the secondary signaling-circuit through the signal A. This circuit is as follows: signal A, wire 51 52, circuit-breaker 53 54, circuit-breaker 55 56, circuit-breaker 57 58, battery 59 60, common battery-wire o 61, circuit-maker 49 50, back to signal A. If the circuit-breakers 53, 55, and 57 in this circuit are closed, as they will be in case there is no train upon subsections O P, P Q, and Q R, the closing of the break by the dropping of circuit-maker 49 will close the circuit through the signal A and draw it to "safety." The engineer seeing the signal A go to "safety" will know there is no train on the track between his own train and signal D and will proceed. If there should at the same time be a train upon the subsection O P, relay 13 in the circuit of battery 9 10 11 12, relay 13 14 15 16 will be demagnetized and circuit-breaker 53 will drop, thus making a break at that point in the circuit through the signal A. This will prevent the circuit-maker 49 from closing the circuit through the signal A, and the signal A will therefore not go to "safety" as the first train enters the subsection N O, and the engineer of this train will accordingly not pass the signal A. In the same way if there be a train upon the subsection P Q as the first train enters subsection N O relay 21 in the circuit of battery 17 18 19 20, relay 21 22 23 24 will be demagnetized and circuit-breaker 55 in the circuit through the signal A will drop and likewise prevent the closing of the break at 49 from closing the circuit through the signal A, and thus prevent that signal from going to "safety." In the same way if there be a train upon subsection Q R the relay 29 in the circuit of battery 25 26 27 28, relay 29 30 31 32 will be demagnetized. The circuit-breaker 57 also in the circuit through the signal A will drop, and thus likewise prevent the closing of that circuit at 49 from closing the circuit through the signal A. In the above-described manner the signal A will not indicate "safety" on the approach of a train proceeding in the direction of the arrow upon the subsection N O unless the track is clear as far as the point R. When the signal A goes to "safety," it makes a break at the circuit-breaker 62 in the circuit through the signal D. In my preferred form of devices the circuit-breaker 62 in the circuit of the signal D is so connected to the mechanism of the signal A that when the latter goes to "safety" the said circuit-breaker 62 is thereby mechanically opened, and it remains open as long as the signal A remains at "safety."

Such a mechanical arrangement is well known in the art and need not be here described. The circuit through the signal D is as follows: signal D 64 65, circuit-maker 66 67 68, battery 59 58, circuit-breaker 57 56, circuit-breaker 55 54, circuit-breaker 53 52 52, circuit-breaker 62 63, back to signal D. This opening of the circuit through the signal D at 62 will prevent the signal D from indicating "safety," as will be hereinafter more fully

explained. The circuit-breaker 103 will also fall upon the demagnetization of relay 5, and this will cause a break at that point in the circuit through the signal B. This signal had previously been broken when the train reached the preceding subsection on the road in the same way that the circuit through the signal D was broken at 62 by the entrance of the train upon subsection N O. The fall of circuit-breaker 103 makes another break in that circuit and insures the signal B from going to "safety" while the train is upon subsection N O.

Second operation, on the train entering subsection O P.—Relay 13 will be demagnetized and circuit-breaker 53 will drop, causing a break at that point in the circuit through the signal A. The signal A will therefore not go to "safety" on the approach of another train upon the subsection N O, but will indicate "danger," thereby protecting the rear of the train on the subsection O P. The fall of the circuit-breaker 53 also makes a break at that point in the circuit through the signal D. The signal D, therefore, will not indicate "safety" so long as the train is upon the subsection O P. The circuit-breaker 101 will also fall, thereby making a break at that point in the circuit through the signal preceding the signal A on the same side of the track in a manner presently to be described, thereby preventing that signal from indicating "safety" upon the approach of a train from the rear. The circuit-breaker 101 is also in the circuit of the signal B, and its fall will cause another break at that point in the said circuit and prevent the signal B from indicating "safety" as long as the train is upon the subsection O P. The effect, therefore, of the presence of a train upon the subsection O P is to prevent signals A, B, and D from indicating "safety."

Third operation, on the entrance of the train upon the subsection P Q.—Circuit-makers 68 and 95 close at once, and circuit-breaker 55 opens. 68 in dropping closes the circuit through the signal C at that point. This circuit is as follows: signal C 70 71, circuit-breaker 72 73, circuit-breaker 74 75, circuit-breaker 76 77, battery 78 79, common battery-wire o 80, circuit-maker 68 69, back to signal C. If circuit-breakers 72, 74, and 76 are closed, as they will be if there is no train upon subsections Q R, R S, or S T, the dropping of circuit-maker 68 will close the circuit through the signal C and send said signal to "safety." If, however, there be a train upon the subsection Q R, it will demagnetize relay 29 and break the circuit at 72 and prevent the signal C from indicating "safety." In the same way if there be a train upon subsection R S relay 37 in the circuit of battery 33 34 35 36 relay 37 38 39 40 will be demagnetized and circuit-breaker 74 will fall, thus breaking the circuit at that point and preventing signal C from indicating "danger." Likewise if there be a train upon subsection

S T relay 45 in circuit of battery 41 42 43 44 relay 45 46 47 48 will be demagnetized and circuit-breaker 76 will drop, thus breaking the circuit at that point and preventing signal C from indicating "danger." If, however, there be no train upon the track between Q and T, signal C will indicate "safety" as the train enters and remains upon subsection P Q, and the engineer seeing the signal C go to "safety" will know that the track is clear to the point T and will proceed past the signal C. The circuit-breaker 55 in falling will open the circuit through signal A in the manner above described and will prevent that signal from going to "safety" upon the entrance of another train on the subsection N O. The fall of this circuit-breaker 55 will also break the circuit of the signal D at that point in the manner above described and prevent that signal from indicating "safety" so long as the train is upon subsection P Q. As the signal C goes to "safety" it mechanically opens circuit-breaker 81 in the circuit of signal F and prevents the latter signal from indicating "safety." The circuit through F is not all shown in the drawing, but is precisely like that through signal D. The effect of the presence of the train upon subsection P Q is to send the signal C to "safety," provided the track is clear from Q to T, and to prevent signals A and D and F from going to "safety" upon the approach of another train.

Fourth operation, on train entering subsection Q R.—Relay 29 will be demagnetized, and circuit-breakers 57 and 72 will drop. 57 in dropping will cause a new break in the circuits through the signals A and D, thereby preventing each of those signals from indicating "safety" on the approach of another train. The fall of circuit-breaker 72 will cause a break at that point in the circuit through the signal C and prevent that signal from indicating "safety" on the approach of another train upon the subsection P Q. This circuit-breaker 72 is also in the circuit through the signal F in the same way that signal-breaker 53 is in the circuit of the signal D. The fall of 72 will therefore break the circuit through the signal F at that point and will prevent the signal F from indicating "safety" on the approach of a train in the reverse direction to that of the arrow. The effect of the presence of the train upon the subsection Q R is accordingly to prevent signals A, D, C, and F from indicating "safety" upon the approach of another train.

Fifth operation, on train entering subsection R S.—Relay 37 is demagnetized, and circuit-makers 66 and 84 close, and circuit-breaker 74 opens. The fall of circuit-breaker 74 causes a new break in the circuits of the signals C and F, and thus prevents either of these signals from going to "safety." The closing of circuit-maker 84 closes the circuit through the signal E at that point, and if the other circuit-breakers in the circuit of this signal are all closed will send the signal E to

"safety" in the same way as the closing of circuit-breaker 49 sends the signal A to "safety" if the circuit-breakers 53, 55, and 57 in the circuit of signal A are all closed. All of the corresponding circuit-breakers in the circuit of the signal E will be closed, provided there is no train upon the three following sections beginning with S T. The effect of the presence of the train upon the subsection R S is accordingly to continue signals C and F at "danger" and send signal E to "safety," provided there be no train upon the next three succeeding subsections.

Sixth operation, on train entering subsection S T.—The circuit-breakers 76 and 88 will fall, the circuit-breaker 76 thereby opening the circuit of signals C and F and continuing them at "danger" and circuit-breaker 88 opening the circuit of the signals E and the next signal succeeding F on the same side of the track in the manner already described. The effect of the passage of a train over the various track-sections in the direction reverse to that indicated by the arrow will be the same on the various circuits and signals as that previously described, except that it will be in the reverse order. Such a train entering upon the subsections T S will break the circuits through the signals C and F at circuit-breaker 76 and continue these signals at "danger" or prevent their passage to "safety" and will break the circuit through the signal E at circuit-breaker 88, continuing that signal at "danger." Upon entering the subsection S R this train will close the break at 66 through the signal-circuit D, and that signal will go to "safety," provided there be no train on the subsection Q R to break the circuit at 57, or upon subsection P Q to break it at 55, or upon subsection O P to break it at 53, or upon subsection N O to send the signal to "safety," and thereby open the circuit-breaker 62. On seeing the signal D go to "safety" the engineer will accordingly know that the track is clear as far as the point N. If there should be a train upon the track at any point between R and N, the signal D will not clear and the engineer will not pass that point. The fall of the circuit-breaker 74 will prevent signals C and F from going to "safety." The effect of the passage of the train farther on the subsections R Q, Q P, and so on will be merely a duplication of that above described on T S and S R.

The number of blocks or subsections and of signals and circuits can of course be increased indefinitely, the arrangement of the same being mere duplications of the devices herein shown and described.

In the place of the circuit-breaker 62 in the circuit of the signal D, which is opened mechanically by the signal A as it goes to "safety" and is held in that position as long as signal A is at "safety," a separate or additional circuit-breaker could be inserted in the circuit of the signal D, adapted to be

opened by the relay 5 when it is demagnetized, so that the presence of a train upon the subsection N O would prevent signal D from going to "safety." I prefer, however, the arrangement shown in the drawing as being of a simpler construction.

It will be noted from the above description that for an inrunning train the signal F guards its rear from the point T to the point P, that 10 the signal D guards its rear from the point R to the point N, and that the signal B guards its rear from the point P to a point beyond the point N. These inrunning blocks, therefore, overlap each other. In the same way 15 it will be observed that the outrunning blocks overlap each other. It will be noted, moreover, that when an outrunning train reaches the point N in advance of the outrunning signal A it puts it to "danger" and also puts 20 the inrunning signal D ahead of the train to or holds it at "danger," and when the train reaches the point o substantially at the signal A it holds the signal to "danger" behind the train. The signals A and D may be 25 termed "corresponding" signals; likewise the signals C and F. The signals A, C, and E face the outrunning trains, or opposite the direction of the arrow, and the signals B, D, and F face the other direction. Any point 30 away from a signal in the direction which it faces may be said to be in advance of or to precede the signal. Points on the other side of the signal would then be said to be in the rear of or to succeed the signal. For example, 35 the point Q with respect to the signals A, C, and E is in the rear of or succeeds the signal A, but is in advance of or precedes the signal E. With respect to the signals B, D, and F the point Q precedes or is in advance of the 40 signal B, but is in the rear of or succeeds the signal D.

My improved device furnishes a simple and efficient means for effectually protecting trains upon a single-track railroad both from 45 collisions in the front and in the rear, and as the signaling-circuits are normally open considerable saving is made in battery-power.

While I prefer to arrange the two sets of signals in the alternate manner shown in the 50 drawing, my improved device can still be operatively used, as will be apparent on inspection to any one skilled in the art, even if the corresponding signals of the series be set opposite or alongside each other. Other modifications which will readily suggest themselves to any one skilled in the art may be made without departing from the spirit of my invention.

What I claim, and desire to secure by Letters Patent, is—

1. In a signaling system for single-track railways, the combination of a series of outrunning blocks and a series of overlapping inrunning blocks, signals for the blocks normally at danger but operating to go to safety in front of the trains which they face, each outrunning signal guarding a portion of the

track which is also guarded by a corresponding inrunning signal, said inrunning signal being located in the rear of its corresponding 70 outrunning signal not less than the distance between the said inrunning signal and the next inrunning signal toward the said outrunning signal, means for operating the inrunning signal to put it to or hold it at danger controlled by an outrunning train from a point in advance of said corresponding outrunning signal and means for operating the outrunning signal to put it to danger controlled by an outrunning train from a point 80 substantially at the said outrunning signal, substantially as set forth.

2. In a signaling system for single-track railways, the combination of a series of outrunning blocks and a series of overlapping 85 inrunning blocks, signals for the blocks normally at danger but operating to go to safety in front of the trains which they face, each outrunning signal guarding a portion of the track which is also guarded by a corresponding inrunning signal, said inrunning signal being located in the rear of its corresponding outrunning signal not less than the distance between the said inrunning signal and the next inrunning signal toward the said outrunning signal, means for operating the inrunning signal to put it to or hold it at danger controlled by an outrunning train from a point in advance of said corresponding outrunning signal, means for operating said inrunning signal to put it to danger controlled by an inrunning train from a point substantially at the inrunning signal, and means for operating the outrunning signal to put it to danger controlled by an outrunning train from a point 95 substantially at the said outrunning signal and by an inrunning train to hold it at or put it to danger from a point in the rear of said outrunning signal and not nearer thereto than the corresponding inrunning signal, substantially as set forth.

3. In an electric signaling system for single-track railways, the combination of a series of outrunning blocks and a series of overlapping inrunning blocks, signals for the blocks normally at danger but operating to go to safety in front of the trains which they face and normally deenergized operating or controlling circuits for the signals, each outrunning signal guarding a portion of the track which is 115 also guarded by a corresponding inrunning signal, said inrunning signal being located in the rear of its corresponding outrunning signal not less than the distance between the said inrunning signal and the next inrunning 120 signal toward the said outrunning signal, a track-circuit for operating the circuit for the inrunning signal to put it to or hold it at danger controlled by an outrunning train from a point in advance of said corresponding 125 outrunning signal, and a track-circuit for operating the circuit for the outrunning signal to put it to danger controlled by an outrunning train from a point substantially at

the said outrunning signal, substantially as set forth.

4. In an electric signaling system for single-track railways, the combination of a series of 5 outrunning blocks and a series of overlapping inrunning blocks, signals for the blocks normally at danger but operating to go to safety in front of the trains which they face and normally deenergized operating or controlling 10 circuits for the signals, each outrunning signal guarding a portion of the track which is also guarded by a corresponding inrunning signal, said inrunning signal being located in the rear of its corresponding outrunning 15 signal not less than the distance between the said inrunning signal and the next inrunning signal toward the said outrunning signal, a track-circuit for operating the circuit for the inrunning signal to put it to or hold it at 20 danger controlled by an outrunning train from a point in advance of said corresponding outrunning signal, a track-circuit for operating the circuit for the inrunning signal to put it to danger controlled by an inrunning 25 train from a point substantially at the inrunning signal, and track-circuits for operating the circuit for the outrunning signal to put it to danger controlled by an outrunning train from a point substantially at the 30 said outrunning signal and by an inrunning train to hold it at or put it to danger from a point in the rear of said outrunning signal and not nearer thereto than the corresponding inrunning signal, substantially as set 35 forth.

5. In an electric signaling system for single-track railways, the combination of a series of 40 outrunning blocks and a series of overlapping inrunning blocks, signals for the blocks normally at danger but operating to go to safety in front of the trains which they face and normally deenergized operating or controlling 45 circuits for the signals, each outrunning signal guarding a portion of the track which is also guarded by a corresponding inrunning signal, said inrunning signal being located in the rear of its corresponding outrunning signal not less than the distance between the said inrunning signal and the next 50 inrunning signal toward the said outrunning signal, a rail-circuit for operating the circuit for the inrunning signal to put it to or hold it at danger controlled by an outrunning train from a point in advance of said corresponding 55 outrunning signal, a rail-circuit for operating the circuit for the inrunning signal to put it to danger controlled by an inrunning train from a point substantially at the inrunning signal, and rail-circuits for operating 60 the circuit for the outrunning signal to put it to danger controlled by an outrunning train from a point substantially at the said outrunning signal and by an inrunning train to put it to or hold it at danger from a point 65 in the rear of said outrunning signal and not nearer thereto than the corresponding inrunning signal, substantially as set forth.

6. In a single-track block-signaling system, two series of signals, each series adapted to act as danger-signals for trains moving in one direction and as opposing signals for trains moving in the other direction, electric signaling-circuits, normally broken at one point, controlled by the train for operating said signals, a circuit-maker at said break in each of 70 said circuits adapted to be closed by the train while on the portion of track in advance of a signal, said signaling-circuits for operating each signal of one series being also controlled by the train while on any portion of the track 75 between said signal of the first series and the opposing signal of the other series which is the second one of said series beyond a preliminary track-section lying immediately in advance of the said signal of the first series, 80 and the circuit for operating each signal of the second series being controlled by the train while on any portion of the track between 85 said signal and the farther end of a preliminary track-section lying immediately beyond 90 the signal of the first series which is next beyond or opposite to the next signal of the second series, substantially as set forth.

7. In a single-track block-signaling system, two series of signals, each series adapted to 95 act as danger-signals for trains moving in one direction and as opposing signals for trains moving in the other direction, said signals being arranged alternately along the track, first a signal from one series, then a 100 signal from the other, and so on, electric signaling-circuits, one for each signal, normally broken at one point, controlled by the train for operating said signals, a circuit-maker in each of said circuits adapted to be closed by 105 the train while on the section of the track immediately in advance of the signal operated by said circuit, the circuit for operating each signal of one series being also controlled by the train while on any portion of the track 110 between said signal of the first series and the opposing signal of the other series which is the second one of said series beyond a preliminary track-section lying immediately in advance of the said signal of the first series, 115 and the circuit for operating each signal of the second series being controlled by the train while on any portion of the track between said signal and the end of a preliminary track-section lying immediately in advance of the 120 signal of the first series which is next beyond or opposite to the next signal of the second series, substantially as set forth.

8. In a single-track block-signaling system, two series of signals, each series adapted to 125 act as danger-signals for trains moving in one direction and as opposing signals for trains moving in the other direction, said signals being arranged alternately along the track, first a signal from one series, then a signal 130 from the other, and so on, insulated sections of track, a track-circuit for each of said sections of track adapted to be operated by the train while on said section, a relay in each of

said circuits, a secondary signaling-circuit, normally broken at one point, adapted to operate each signal, a circuit-maker at said break in each signaling-circuit adapted to be closed by the train while on the section of track in advance of the signal in said circuit, circuit-breakers in each of said signaling-circuits adapted in the signal-circuits of one series of said signals to be operated by the relays in three of said track-circuits and in the signaling-circuits of the other series of signals to be operated by the relays in four of said track-circuits, substantially as set forth.

9. In a single-track block-signaling system, 15 two series of signals, each series adapted to act as danger-signals to trains moving in one direction and as opposing signals to trains moving in the other direction, said signals being arranged alternately along the track, 20 first a signal from one series, then a signal from the other and so on, insulated sections of track, a normally closed track-circuit for each of said sections of track adapted to be operated by the train while on the said section, a relay in each of said circuits, a secondary signaling-circuit, normally broken at one point, adapted to operate each signal, a circuit-maker in each of said signaling-circuits adapted to be closed by the train while 25 30 on the section of track immediately in advance of the signal of said circuit, circuit-breakers in each of said signaling-circuits, adapted in the signaling-circuits of one series of said signals to be operated by the relays in three of said track-circuits, and in the signaling-circuits of the other series to be operated by the relays of said track-circuits, substantially as set forth.

10. In a single-track block-signaling system, 40 two series of signals, each series adapted to act as danger-signals for trains moving in one direction and as opposing signals to trains moving in the other direction, insulated sections of track, track-circuits, including the 45 said insulated sections, adapted to be operated by the train, relays in said circuits, a secondary signaling-circuit, normally broken at one point, adapted to operate each signal, a circuit-maker at the break in each of said 50 circuits adapted to be closed when the train is on the section of track immediately in advance of the signal of said circuit, circuit-breakers in each of said signaling-circuits adapted in the signaling-circuits of one series 55 of said signals to be operated by the relays of the track-circuits covering the portions of track between a signal of said first series and the opposing signal of the other series which is the second one of said series beyond a preliminary track-section which lies immediately 60 in advance of the said signal of the first series, and adapted in the signaling-circuits of the other series of said signals to be operated by the relays of the track-circuits covering 65 the said preliminary track-sections and the track-sections between it and the second signal of the said other series beyond said pre-

liminary track-section, substantially as set forth.

11. In a single-track block-signaling system 70 two series of signals, each series adapted to act as danger-signals for trains moving in one direction and as opposing signals for trains moving in the other direction, insulated sections of track, track-circuits, normally closed, 75 including said insulated sections and adapted to be operated by the train while on said sections, relays in said circuits, a secondary signaling-circuit normally broken at one point adapted to operate each signal, a circuit-maker at the break in each of said circuits adapted to be closed by the train while on the section of track immediately in advance of the signal of said circuit, circuit-breakers in each of said signaling-circuits adapted in 80 the signaling-circuits of one series of said signals to be operated by the relays of the track-circuits covering the sections of track between a signal of said first series and the opposing signal of the second series which is 85 the second one of said second series beyond a preliminary track-section which lies immediately in advance of the said signal of the first series, and adapted in the signaling-circuits of the other series of said signals to be 90 operated by the relays of the track-circuits covering the said preliminary track-section and the track-sections between it and the second signal of the said second series beyond said preliminary track-section, substantially 95 as set forth.

12. In an electric signaling system for single-track railways, the combination of a rear signal normally at danger, an opposing signal normally at danger, line-circuits for the signals and normally closed rail-circuits operated by the passage of a train for controlling or operating said signals, an electromagnetically-operated switch located in one of said rail-circuits to cause the rear signal to show 105 safety before an approaching train when the track-section guarded by the signal is clear, a circuit-breaker to cause said signal to show danger as long as the train is in said guarded track-section, and a mechanical means to prevent the opposing signal in advance of the train from showing clear until the train has passed it, substantially as set forth.

13. In an electric signaling system for single-track railways, the combination of a series of rear signals normally at danger, a series of corresponding opposing signals normally at danger, line-circuits for the signals and normally closed rail-circuits operated by the passage of a train for controlling or operating said signals, an electromagnetically-operated switch located in one of said rail-circuits to cause a rear signal to show safety before an approaching train when the track-section guarded by the said signal is clear, a circuit-breaker to cause said signal to show danger as long as the train is in said track-section and until after it has passed beyond the next rear signal in advance of the train,

and a mechanical means for preventing the corresponding opposing signal in advance of the train from showing clear until the train has passed it, substantially as set forth.

5 14. In an electric signaling system for single-track railways, the combination of a rear signal normally at danger, an opposing signal normally at danger, line-circuits for the signals and normally closed rail-circuits operated by the passage of a train for controlling or operating said signals, an electromagnetically-operated switch located in one of said rail-circuits to cause the rear signal to show safety before an approaching train when 15 the track-section guarded by the signal is clear, a circuit-breaker to cause said signal to show danger as long as the train is in said guarded track-section, and a mechanical means for preventing the opposing signal in 20 advance of the train from showing clear until the train has passed it, said rear signals serving to control the setting or continuing of its corresponding signal as an opposing signal, substantially as set forth.

25 15. In an electric signaling system for single-track railways, the combination of a series of rear signals normally at danger, a series of corresponding opposing signals normally at danger, line-circuits for the signals and normally closed rail-circuits operated by the passage of a train for controlling or operating said signals, an electromagnetically-operated switch located in one of said rail-circuits to cause a rear signal to show safety before an 30 approaching train when the track-section guarded by said signal is clear, a circuit-breaker to cause said signal to show danger as long as the train is in said track-section and until after it has passed beyond the next 35 rear signal in advance of the train, and a mechanical means for preventing the corresponding opposing signal in advance of the train from showing clear until the train has passed it, said rear signals serving to control the setting or continuing of its corresponding signal as an opposing signal, substantially as set forth.

40 16. In an electric signaling system for single-track roads, the combination of a series of outrunning blocks and a series of overlapping inrunning blocks, signals for the blocks and operating or controlling line-circuits for the signals, each outrunning signal guarding a portion of the track which is also guarded by 45 a corresponding inrunning signal, said inrunning signal being located in the rear of its corresponding outrunning signal not less than the distance between the said inrunning signal and the next inrunning signal toward the 50 said outrunning signal, a track-circuit for operating the circuit for the inrunning signal to put it to danger controlled by an outrunning train and located in advance of said corresponding outrunning signal, and a track- 55 circuit for operating the circuit for the outrunning signal to put it to danger controlled by an outrunning train and located substan-

tially at the said outrunning signal, the several circuits of the blocks being so arranged that the inrunning signals are connected together and the outrunning signals are connected together and the inrunning and outrunning signals are interconnected, substantially as set forth.

60 17. In an electric signaling system for single-track roads, the combination of a series of outrunning blocks and a series of overlapping inrunning blocks, signals for the blocks and operating or controlling line-circuits for the signals, each outrunning signal guarding a portion of the track which is also guarded by 65 a corresponding inrunning signal, said inrunning signal being located in the rear of its corresponding outrunning signal not less than the distance between the said inrunning signal and the next inrunning signal toward the said outrunning signal, a track-circuit for operating the circuit for the inrunning signal to put it to danger controlled by an outrunning train and located in advance of said corresponding outrunning signal, a track-circuit 70 operating the circuit for the inrunning signal to put it to danger controlled by an inrunning train and located substantially at the inrunning signal, a track-circuit for operating the circuit for the outrunning signal to put it to danger controlled by an outrunning train and located substantially at the said outrunning signal, and a track-circuit for operating the circuit for the outrunning signal to put it to danger controlled by an inrunning train and located in the rear of said outrunning signal and not nearer thereto than the corresponding inrunning signal, the several circuits of the blocks being so arranged 75 that the inrunning signals are connected together and the outrunning signals are connected together and the inrunning and outrunning signals are interconnected, substantially as set forth.

80 18. In an electric signaling system for single-track roads, the combination of a series of outrunning blocks and a series of overlapping inrunning blocks, signals for the blocks and operating or controlling line-circuits for the signals, each outrunning signal guarding a portion of the track which is also guarded by 85 a corresponding inrunning signal, said inrunning signal being located in the rear of its corresponding outrunning signal not less than the distance between the said outrunning signal and the next inrunning signal toward the said outrunning signal, a rail-circuit for operating the circuit for the inrunning signal to put it to danger controlled by an outrunning train and located in advance of said corresponding outrunning signal, a rail-circuit 90 for operating the circuit for the inrunning signal controlled by an inrunning train and located substantially at the inrunning signal, a rail-circuit for operating the circuit for the outrunning signal to put it to danger controlled by an outrunning train and located substantially at the said outrunning signal,

and a rail-circuit for operating the circuit of the outrunning signal to put it to danger controlled by an inrunning train and located in the rear of said outrunning signal and not 5 nearer thereto than the corresponding inrunning signal, substantially as set forth.

In testimony whereof I have signed my

name to this specification in the presence of two subscribing witnesses.

WILMER W. SALMON.

Witnesses:

L. THOMAS,

JOS. P. VARCHER.
